Sheldon King

By Charles Turner Brown,
Atty.

UNITED STATES PATENT OFFICE.

SHELDON KING, OF DETROIT, MICHIGAN.

RAZOR SHARPENER FOR RAZOR BLADES.

Application filed January 18, 1923. Serial No. 613,558.

To all whom it may concern:

Be it known that I, SHELDON KING, a citizen of the United States, and a resident of the city of Detroit, in the county 5 of Wayne and State of Michigan, have invented certain new and useful Improvements in Razor Sharpeners for Razor Blades, of which the following, when taken in connection with the drawing accompanying 10 and forming a part hereof, is a specification.

This invention relates to a razor sharpener in which a plurality of rapidly revolving rolls which are provided with abrading surfaces of different degrees of fineness, are employed.

Among the objects of this invention are to obtain razor sharpeners of the kind named which will form, together with the 20 motive power therefor, a single unit; to obtain a razor sharpener which is simple in construction, is durable, and is not liable to break or get out of order; and an additional object is to obtain a razor sharpener of the kind named by means of which a razor blade may readily be moved from a position in which it may be operated on by rolls having a given degree of abrading surface, to rolls of a different degree of 25 abrading surface. A further object is to obtain a razor sharpener of the kind named by means of which both sides of a razor blade adjacent to the cutting edges thereof may easily be alternately applied to the 30 abrading surface of the rolls corresponding with the position of said razor blade. An additional object is to obtain means for firmly holding a razor blade which is to be sharpened by the machine in such position that when said blade is presented to the abrading surfaces of said rolls it will 35 be suitably positioned to properly sharpen the same.

I have illustrated a machine embodying 40 the invention in the drawing referred to, in which—

Fig. 1 is a front elevation.

Fig. 2 is a vertical section on line 2—2 of Fig. 1, viewed as indicated by arrows.

Fig. 3 is a vertical section on line 3—3 of Fig. 1, viewed as indicated by arrows, and showing a handle with a razor blade therein in a neutral position to permit said

razor blade to be applied to the surface of a determined one of the corresponding rolls. 55

Fig. 4 is a top plan view of the razor blade handle, on an enlarged scale.

And Fig. 5 is a side elevation of said handle, also on an enlarged scale.

A reference character applied to designate a given part indicates said part throughout the several views, wherever the same appears.

A represents the base of the machine; B, B', represent standards which are rigidly secured to base A, as by bolts b, b'. C, C', represent shafts which are, respectively, rotatably mounted in journal bearings in standards B, B'. D, D', respectively represent gear wheels, which are rigidly secured on shafts C, C', with the teeth thereof intermeshing. X represents an electric motor, and E the driving shaft thereof. F represents a gear wheel which is rigidly secured on shaft E so that the teeth thereof intermesh with the teeth of gear wheel D. G, H, I, and J, respectively represent rolls which are rigidly secured on shaft C, as by pins g, h, i, j, and k, which, respectively, extend through the hubs of said rolls and through said shaft. G', H', I' and J', respectively represent rolls corresponding with rolls G, H, I and J, which are rigidly secured, as by pins g', h', i', j' and k' to shaft C'. The several rolls are surfaced with different grades of abrading material, as say, rolls G, G' are surfaced with what I term coarse abrading material, rolls H, H', are surfaced with what I term medium abrading material, and I, I' with fine abrading material, while rolls J, J', are, preferably, surfaced with leather facing material. The several hubs of the rolls serve also to hold said rolls in spaced relation to each other, and to hold the end rolls in spaced relation to the standard B, B'. The standards B, B', are, respectively, provided with a recess K, K', see Figs. 2 and 3; and L, L', respectively represent rods which serve the double function of tie rods between the standards, and guides for the blade holder about to be described. Rods L, L', respectively, are rigidly held in standards B, B', by screws l, l, and l', l'.

The ends of said rods are provided with apertures having internal screw threads 100 105

corresponding with the screw threads on said screws l , l , and l' , l' . The foregoing recited manner of securing rods L , L' in standards B , B' , is to enable the operator 5 to insert the handle M in place on said rods L , L' , by passing it through said recesses K , K' , in placing said handle on said rods and removing it therefrom. The handle M comprises members which are substantially 10 duplicates, and which are pivotally joined by rod or pin m , extending through abutments m' , m' , m'' , m'' , represent abutments on the inner faces of the members of handle M , the opposing faces of said 15 abutments m'' , m'' being bevelled, and N represents a lever which is pivotally mounted on pin n . The pivotally mounted end n' and n'' of said lever N being bevelled correspondingly with the abutments m'' , m'' , 20 so that the turning of said lever on its pivot n , will force the ends of the members of handle M where said lever N and abutments m'' , m'' , are positioned, apart, thereby forcing the gripping ends O , O , 25 (Figs. 4 and 5), of the members of the handle together, to hold a safety razor blade, as P , Fig. 3, placed between them, firmly in place. Q , Q' are projections on the outer sides of the members of the handle 30 M , in spaced relation with the gripping ends O , O , of said handle, so that when the handle is inserted between the rods L , L' , with said abutments in contact with said rods, as illustrated in Fig. 3, the cutting edge of said razor blade P will be in suitable 35 relation with the surfaces of the several rolls, so that as the free end of said handle M is moved up or down, turning said handle on one or the other of said rods L , L' , the edge of the razor blade which is to be sharpened, will be brought in proper contact with the abrading surface of rolls corresponding with the position, laterally, of said handle between said rods. 40 To operate the machine the motor X is energized, and the several rolls are rapidly revolved. The handle M , having a razor blade secured between the jaws O , O , is inserted, as recited, between the rods L , L' , 45 and in front of the determined pairs of said rolls. The handle M , M , is turned on said rods so as to alternately bring said razor blade in contact with a lower and an upper one of said determined pair of rolls, and said razor blade is ground thereby. When suitably ground by said determined rolls the handle is turned to a neutral position and moved along said rods L , L' to proper position between the adjacent rolls, having a finer abrading surface. The operation last above described is continued, until the razor blade is in suitable 50 position between the rolls having the leather finishing surface, to which surfaces it is then subjected, until operations on the blade 55

are completed, when said handle may be removed from the machine, either by withdrawing it directly therefrom, or by continued sliding of the handle along the rods L , L' . 70

It is to be understood that the condition of a razor blade determines how many of the several rolls are to be used to sharpen it, all of said rolls being required only when said blade is very dull. 75

I claim:

1. A razor sharpener comprising standards respectively provided with recesses on one side thereof, a plurality of parallel rods connecting said standards, parallel shafts rotatably mounted in said standards, means to rotate said shafts in opposite directions, rolls arranged in pairs rigidly mounted on said shafts, abrading surfaces on said rolls, the abrading surfaces of each pair being substantially alike and the abrading surfaces of different pairs being different, in combination with a handle provided with jaws at one end thereof adapted to hold a razor blade, and abutments on the outer faces thereof, and said handle adapted to be placed between said rods with the razor in said jaws in spaced relation with the abrading surfaces of the several rolls, said parallel rods respectively arranged to alternately form the fulcrums of said handle and said abutments respectively arranged to alternately co-act with said rods to determine the position of said handles on said fulcrums. 90

2. A handle comprising members pivotally connected together, abutments on the outer faces of said members, in spaced relation to the edges of the jaws of said members, opposing abutments on said members, adjacent to one end thereof and jaws at the other end of said members, a pivotally mounted lever between said opposing abutments arranged to co-act with said abutments to control the relative position of said jaws, in combination with a razor sharpener comprising rotatably mounted rolls provided with abrading surfaces and with a plurality of parallel rods respectively parallel to said rolls and adapted to alternately form fulcrums, said abutments on the outer faces of the members of said handle arranged to co-act with said parallel rods to determine the position of said handle on said fulcrums and control the relation of said jaws to said rolls. 110

3. A base, standards rigidly secured to said base, said standards respectively provided with recesses on one side thereof, a plurality of parallel rods secured in and connecting said standards adjacent to said recesses, in combination with parallel shafts rotatably mounted in said standards, intermeshing gear wheels rigidly secured on said shafts, and a plurality of 125

5 pairs of rolls rigidly secured in spaced relation on said shafts, each pair of said rolls provided with abrading surfaces substantially of the same grade and in spaced relation, the abrading surfaces of different pairs being of different grades, means secured to said base to rotate said gear wheels, a razor blade handle provided with abutments on the outside face of the members thereof and
10 adapted to be inserted between said rods and to hold a razor blade held in said handle in determined relation to the abrading

surfaces of the several pairs of rolls, said parallel rods respectively arranged to alternately form the fulcrums of said handles and said abutments respectively arranged to alternately co-act with said rods to determine the position of said handles on said fulcrums. 15

SHELDON KING.
